UNITED STATES PATENT OFFICE.

WILBUR A. GARRITT AND JAMES H. ENGEBRIGTSON, OF SIOUX CITY, IOWA.

SIGN-DISPLAYING DEVICE.

Application filed July 19, 1920. Serial No. 397,251.

To all whom it may concern:

Be it known that we, WILBUR A. GARRITT and JAMES H. ENGEBRIGTSON, citizens of the United States, and residents of Sioux City, in the county of Woodbury and State of Iowa, have invented certain new and useful Improvements in Sign-Displaying Devices, of which the following is a specification.

10 Our invention has for its primary object the production of a mechanically operated device for successively displaying sign cards. A further object of the invention is the production of such a device which operates automatically and dependably, unattended.

15 A still further object of the invention is the production of a device of this class, thoroughly efficient and dependable in operation, yet simple and inexpensive in both 20 construction and operation.

25 These and other objects and advantages we successfully attain in the embodiment hereinafter described, defined in the appended claim and illustrated in the accompanying drawings, which form a part of this application and in which like characters of reference indicate corresponding parts throughout the several views, of which:

30 Fig. 1 is a front elevation of a device, constructed in accordance with the invention.

Fig. 2 is a front elevation of the same with the front of the case removed and parts cut away, and Fig. 3 is a transverse section of the same.

35 Although we have illustrated and herein-after described but one form of the invention, we would not be understood as being limited to this specific construction, for various alterations and modifications may be 40 made in the details of construction and arrangement of parts disclosed without departing from the spirit and scope of the invention as defined in the appended claim.

45 Referring, now, to the illustrations, the superstructure of the device preferably consists of a casing, including a floor, 4, an upright rear wall, 5, and an inclined front wall, 6, having an intermediate opening, 7, through which the signs are revealed as will 50 presently appear.

55 8 are the side walls of the casing, and within the lower portion of the casing and adjacent the said side walls are positioned sprocket or belt wheels, 9, carried by a shaft, 10, journaled in the side walls. The said wheels, 9, are connected, respectively, by

sprocket chains, 11, or belts, with small sprocket-wheels, or belt-wheels 12, positioned a distance above the wheels, 9, and rotatably supported by the walls, 8. The 60 chains or belts, 11, are inter-connected by a transverse rod, 13. 14 are sign cards positioned between the chains and provided, a distance from their upper edges, with lateral studs, 15, preferably provided with 65 heads, 16. 17 are rearwardly inclined rails, suitably mounted on the walls, 8, to engage the studs, 15, to normally support the cards and permit them to gravitate rearwardly, as 70 will later be made more clear.

Adjacent their lower edges the cards are provided on their backs with hooks, 21. Between the rear leads of the chains, 11, extends a cross-member, 18, suitably suspended as by hangers, 19, which depend from the 75 guide rails, 17, the said cross-member, 18, being so positioned that upon it may rest the lower edge of the rearmost of the idle cards, 14, and the rear ends of the guide members, 17, are provided with suitable 80 stops, 20, engageable by the studs, 15, to prevent displacement of the rear card.

On the backs of the cards, a short distance above their lower edge, are hooks, 21, so positioned that when the belts are driven in the 85 direction indicated by the arrow in Fig. 3, those of the rearmost of the idle cards will be engaged by the cross-member, 18, to carry such card upwardly to the position indicated at 14^A, forward tilting of the cards in this 90 position being prevented by virtue of engagement of the studs, 15, behind the rear upright edges, 22 of guide-members, 23, suitably supported by the walls, 8.

The front edges of the guide members, 23, 95 are declined forwardly as at 24, and their upper end portions are curved rearwardly adjoining the rear edges, 22, at points, 25. As the rod, 13, approaches the highest point of its travel, the upper edge of the card fulcrums against the rear wall of the casing, and as the rod moves forwardly and downwardly as shown at 14^B, the studs, 15, pass over the points, 25, and slidably engage the front edges, 24, of the guides, 23. As the 100 movement of the chains continues, the card is permitted to gravitate to the position indicated at 14^C, in which position it is visible through the opening, 7, of the casing, and is supported by a cross-member, 26. As 105 the card approaches this position, the studs, 15, slidably engage guide-members, 27, and

finally drop into notches, 28, in the lower end portions of the said guides, 27, to prevent the card from falling rearwardly. The rod, 13, then repeats its course, carrying the 5 next of the idle cards, which, coming in contact with the lower portion of the first card, forces the latter rearwardly from the cross-member, 26, which permits it to precipitate, and cause the studs, 15, thereof to disengage 10 from the notches, 28, and slide rearwardly on the guide, 17, thus carrying the card to the foremost of the idle cards. Thus the operation is repeated to successively display 15 the cards.

15 Around the opening, 7, the front wall of the casing is preferably provided with inner flanges, 29, above the upper one of which is an illuminating element, 30, which projects its rays through a slot, 31, in the flange and 20 upon the card displayed.

Having thus described our invention, what we claim as new and desire to secure by Letters Patent of the United States, is:

A display device consisting of a suitable 25 frame, two pairs of wheels positioned one

pair above the other, endless chains interconnecting the pairs, a rod interconnecting the chains, rearwardly inclined rails carried by the frame, display cards normally positioned one in front of another and provided with lateral projections slidably engageable with the rails to normally support the cards, a support for the rearmost card, hooks on the backs of the cards engageable by the rod, whereby the cards are successively carried upwardly and forwardly and then permitted to gravitate, a front support to stop gravitation of the cards for display, and permit disengagement of the rod from the hooks and means for preventing rearward tilting of the cards when displayed, the front support and said means being so positioned and related that each gravitating card will engage and force the preceding cards from said front support and permit its projections to slidably engage the rails.

In testimony whereof, we have hereunto set our hands this 14th day of July, 1920.

WILBUR A. GARRITT.

JAMES H. ENGBRIGTSON.
